(57) **CLAIM**

The ornamental design for a ceiling fan, as shown and described.

DESCRIPTION

The file to this patent contains at least one photograph executed in color. Copies of this patent with color photographs will be provided by the Office upon request and payment of the necessary fee.

FIG. 1 is a bottom plan view of a ceiling fan.

FIG. 2 is a top plan view thereof; and,

FIG. 3 is a side elevational view, the other sides being substantially identical except for the position of the blades.
